UNITED STATES PATENT OFFICE.

ADOLPH WAGNER, OF ST. LOUIS, MISSOURI.

SLIDING-DOOR POCKET.

No. 875,870.

Specification of Letters Patent.

Patented Jan. 7, 1908.

Application filed July 31, 1907. Serial No. 386,372.

To all whom it may concern:

Be it known that I, ADOLPH WAGNER, a citizen of the United States, residing at St. Louis, State of Missouri, have invented certain new and useful Improvements in Sliding-Door Pockets, of which the following is a full, clear, and exact description, reference being had to the accompanying drawings, forming a part thereof.

10 My invention has relation to improvements in sliding-door pockets; and it consists in the novel construction of pocket more fully set forth in the specification and pointed out in the claims.

15 In the drawings, Figure 1 is an outside elevation of the pocket-wall, with parts broken away to show the successive layers composing the wall; Fig. 2 is a transverse vertical section on line 2—2 of Fig. 1; Fig. 3 is a horizontal section on line 3—3 of Fig. 1; Fig. 4 is a perspective of the shoe which receives the bottom of the tee iron entering as a structural feature of the pocket-wall; and Fig. 5 is an elevational detail of the lower portion of one of the tees and lathing secured thereto.

20 The object of my invention is to construct a pocket for sliding-doors with a view of reducing the space generally occupied by the walls of such pocket as ordinarily constructed.

25 The ordinary wooden studs which are so universally employed for the walls of sliding-door pockets are objectionable on account of the undue thickness which they impart to such walls, this thickness in turn reducing the available area of the rooms separated by such walls. My invention contemplates the substitution for such studs, of suitable structural members in the form of T-irons, the disposition of whose flanges permits the lathing to be secured in such a way as to materially reduce the cross-sectional dimension of the resulting pocket and the wall by which such pocket is defined.

30 The advantages of the invention will be better apparent from a detailed description thereof which is as follows:

35 Referring to the drawings, 1, 1, represent a series of structural members in the form of T-irons set in opposite parallel rows with the flanges of the tees facing each other or pointing toward the interior of the pocket P, the webs pointing outwardly. The lower ends of the tees rest in shoes 2, of a suitable formation to admit the flange and web of the tee, the shoe being provided with a flange 2'

by which it is secured to the floor F. The upper ends of the tees are secured to a wooden header 3 forming the roof of the pocket. Since the tee is received loosely in the shoe 60 2, it follows that all shrinkage is allowed for, the tee freely playing in the shoe in response to any strains to which the parts may be subjected as a result of such shrinkage. The bottom of the tee rests on a plate 4, and 65 bearing against and overlapping said plates between each pair of tees is a ground strip 5 to which the lower end of the base 6 is nailed, the upper end of said base being nailed to the upper strips 7 disposed between the webs of 70 contiguous tees. The strips 7 are carried by the wooden vertical strips 8 disposed along the outer faces of the flanges of the tees, said vertical strips carrying the lathing 9 over which is finally laid the plaster 10. 75 Since the web of the tee projects somewhat into the plaster coat, the latter is thinnest immediately opposite the edge of the web, and as a precaution against cracking or flaking off, I provide a background of wire-netting 11 the full height of the tee, the strip of netting passing over the edge of the web and being secured to the lathing on each side thereof (Fig. 1). The netting serves to reinforce the plaster coat at this point and prevents the same from cracking and peeling off. 80

85 The rear end of the pocket is closed by a wall 12. The outer pair of tees are provided with vertical wooden studs 13 secured to the tee flanges, and provided with basal dowel pins 14 loosely entering the floor to permit of shrinkage. To the sides of these studs are secured the vertical finish panels or strips 15, to the front of which are in turn secured the frame pieces 16, and to these in turn the friction strips 17. Between the walls of the pocket slides the door D which is suspended by a hanger 18 from a trolley or wheel 19 running in a boxing 20 secured to the header 3. In lieu of tees, I may substitute angle-bars in pairs, which would be a full equivalent for the tees as obvious.

90 It will be seen that by the use of tees, the lathing can be secured on the flanged portions of the tees, this arrangement necessarily reducing the thickness of the completed wall in which the pocket is formed, over the thickness of the wall of a corresponding pocket built from wooden studs where the lathing is nailed to the outer faces of such studs. The present arrangement too results in a rigid pocket whose walls are always true. 105 110

2
and the danger of binding between the parts is altogether eliminated.

Having described my invention what I claim is:

- 5 1. A wall for sliding-door pockets having a series of tees entering as component elements of said wall, the flanges of the tees facing the pocket, and means for securing suitable lathing along the outer faces of the flanges of the 10 tees, said lathing being disposed between said faces and the edges of the tee-webs substantially as set forth.
- 15 2. A sliding-door pocket having inclosing side walls composed of a series of tees with flanges facing the pocket, shoes resting on the floor for receiving the bottoms of the tees, a header for securing the flanges of the tees, lathing secured to the flanges of the tees, and a plaster coat carried by the lathing, substantially as set forth.
- 20 3. A sliding-door pocket having inclosing side-walls composed of a series of tees with flanges facing the pocket, shoes resting on the floor and receiving the tees, vertical wooden strips secured along the outer faces 25 of the flanges, lathing nailed to said vertical strips, and a coat of plaster on the lathing, substantially as set forth.
- 30 4. A sliding-door pocket having inclosing side-walls composed of a series of tees with flanges facing the pocket, shoes for supporting the bottoms of the tees, a header for securing the upper ends of the tees, vertical strips disposed along the outer faces of the

flanges on each side of the webs of the tees, 35 lathing secured to said strips, a reinforcing strip of wire netting passed over the edge of the web of each tee and secured to the lathing, and a covering of plaster for the lathing and netting aforesaid, substantially as set 40 forth.

5. In a sliding-door pocket having inclosing side walls terminating in a pair of tees having flanges directed toward the pocket, a stud secured to the outer face of the outer 45 flange of each tee, a finish strip secured to the side face of each stud, a frame secured to the outer edge of the strip, a friction-strip secured to the finish-strip, the stud having a bottom pin loosely entering the floor to allow 50 for shrinkage, substantially as set forth.

6. In a sliding-door pocket, a wall having a series of tees disposed with flanges facing the pocket, shoes on the floor for receiving the bottoms of the tees, plates supporting the 55 tees, ground strips abutting against the plates, upper strips disposed above the ground strips between the webs of contiguous tees, and a base strip or board secured to the aforesaid ground strips and upper strips, 60 substantially as set forth.

In testimony whereof I affix my signature, in presence of two witnesses.

ADOLPH WAGNER.
